UNITED STATES PATENT OFFICE.

ROBERT H. COWDERY, OF GENEVA, OHIO, ASSIGNOR TO THE AMERICAN FORK & HOE COMPANY, OF CLEVELAND, OHIO, A CORPORATION OF OHIO.

DESIGN FOR A BOW FOR ARCHERY.

Application filed October 28, 1927. Serial No. 23,917. Term of patent 14 years.

To all whom it may concern:

Be it known that I, ROBERT H. COWDERY, a citizen of the United States, residing at Geneva, in the county of Ashtabula and State of Ohio, have invented a new, original, and ornamental Design for Bows for Archery, of which the following is a specification, reference being had to the accompanying drawing, forming part thereof.

Fig. 1, is a side elevational view of a bow for archery showing my new design.

Fig. 2 is a perspective view taken from the line 2—2 of Fig. 1, looking in the direction of the arrows.

I claim:

The ornamental design for a bow for archery substantially as shown.

ROBERT H. COWDERY.
